(57) **CLAIM**

The ornamental design for the pre-cut body tape for the back, as shown and described.

DESCRIPTION

This application is related to U.S. Design patent application Ser. No. 29/335,603, entitled "Adhesive Tape", filed on Apr. 17, 2009, and the specification, drawings and claim thereof are incorporated herein by reference.

FIG. 1 is a perspective view of a pre-cut body tape for the back;

FIG. 2 is a right side view of a pre-cut body tape for the back; and,

FIG. 3 is a left side view of a pre-cut body tape for the back.

The broken line showing of the human forms is for the purpose of illustrating how the pre-cut body tape for the back is applied and forms no part of the claimed design.
